BUILDING CONSTRUCTION

James Slayter and Howard W. Collins, Newark, Ohio, assignors, by means assignments, to The Ingleside Company, Newark, Ohio, a corporation of Ohio

Application May 17, 1937, Serial No. 143,203

4 Claims. (Cl. 20—1)

This invention relates to building constructions and refers more especially to the construction and assembly of preformed wall and floor sections.

Many have realized that prefabricated houses, entirely constructed in factories where production methods and their resulting economy may be practiced, would solve the problem of providing well constructed low cost houses for the general public. Numerous attempts have been made in this field, but difficulties have been encountered in designing preformed sections capable of being readily secured together by relatively simple fastening means without considerable readjustment of the sections on the building site and without resorting to exposed and complicated fastening means.

It is therefore one of the principal objects of this invention to remove the above difficulties by providing floor and wall sections preformed in accordance with accepted building construction and capable of being readily assembled on the building site in such a manner that none of the connections are visible in the finished house. A further object of the invention is the assembly of the wall section upon the floor section in a manner to insure against settling of the walls due to shrinkage of the building materials. In accordance with this invention, shrinkage is reduced to the minimum by supporting the side wall units on the joists of the floor section below the top edges of the joists and the top edge of the floor section. As a result, the wall sections are exposed to the shrinkage of only a fraction of the width of the joists.

Numerous other objects of the invention, as well as the foregoing, will be apparent as the description proceeds.

In the drawings:

Figure 1 is a perspective view showing a portion of a building with wall and floor sections joined.

Figure 2 is a section taken substantially along lines 2—2 of Figure 1.

Figure 3 is a section taken along lines 3—3 of Figure 2.

Figure 4 is a portion of the building taken substantially along lines 4—4 of Figure 1.

Figure 5 is a section along lines 5—5 of Figure 4.

Figure 6 is a portion of the building taken substantially along lines 6—6 of Figure 1.

Figure 7 is a sectional view of Figure 6 with the parts broken away.

Figure 8 is a portion of the building taken substantially along lines 8—8 of Figure 1, and

Figure 9 is a sectional view of Figure 8 with parts broken away.

With reference to the drawings more in detail, it will be seen that in Figure 1 several wall and floor sections are shown in assembled relationship. The present invention deals particularly with the construction of these preformed sections in a manner rendering it possible to readily secure the sections in assembled relationship.

This type of preformed section is adaptable to practically any of the generally used house foundations. In Figure 1 there is shown a portion of a concrete foundation 20 having walls 21 and 22. With this type of foundation suitably supported I-beams, such as 23, are used. Upon these supporting means floor sections 24 are seated. These sections are composed of a framework of parallel joists 25 extending parallel to the side wall 21 of the foundation and interconnected by the cross member 26. The joist 27 adjacent this wall differs from the others in that it is L-shaped in cross-section. The lateral extending portion 28 of this joist extends over the top 29 of the wall 21 and is supported thereby. This joist is of the same thickness as the joists 25.

The wall engaging ends 30 of the joists 25 are notched to provide a projection 31 at the lower edge thereof and these projections engage the wall 22 for substantially the full width of that wall. Between projections 31 are located filler blocks 32 also extending substantially the full width of the wall 22 and secured to the projections. These blocks have a vertical thickness the same as the vertical thickness of the projections 31 so that their upper surfaces are in the same plane. It will be understood that the extending portion 28 of joist 27 is designed so that its upper surface will also be in the same plane with that of the projections 31 and the filler blocks 32. Over the completed framework of the floor section upper and lower building material 33 and 34 may be placed. We prefer to use for the upper material 33 fibre board, or the like, for carpeting or flooring may be easily added thereto. The lower building material 34 may be plaster board, gypsum board, or the like. This is preferably used as it makes an excellent ceiling material. Building material 34, however, is not necessary on the first floor sections, unless a finished ceiling in the basement is desired.

The floor sections may be made sufficiently long so that the joists will extend from wall 22 to the opposite wall. Normally, however, a section is made so that one end will rest upon supporting

beams 23 and the other end upon wall 22. Where the sections come together at the supporting beams 23, securing strips may be attached to the building material 40 of each section. The means 5 of connecting the sides of adjoining sections is the subject matter of our copending application Serial No. 143,202, filed May 17, 1937.

It will be apparent that the building material 33 and 34 are placed over the framework in such 10 manner that when the floor sections are assembled, this material will extend from wall to wall.

The wall sections 35 are constructed over a framework of vertical studding 36 with horizontal studs 37 and 38 across the top and bottom portions 15 respectively. These as well as intermediate supports 39 are secured together in the normal building manner. Over this framework is located inner and outer building material 40 and 41. The outer material extends from the top of stud 20 37 to the bottom of stud 38 and over it shingles, clapboard, or the like may be attached. The inner material is also attached to the top of the stud 37, but stops short of the bottom stud about twelve inches or so.

25 The assembly of the sections is as follows: Upon the supporting walls 21, 22, in which bolts 42 have been imbedded, termite treated plates 43 and 44 are attached and bolted thereto. The floor sections are then seated upon these plates. 30 As seen in Figures 4 and 5, the projections 31 will rest upon plates such as 44 and may be nailed or otherwise secured thereto. As seen in Figures 2 and 3, the projection 28 will seat upon plates such as 43 and may also be secured thereto. Having secured the floor sections, the wall sections 35 are now placed upon projections 28 and 31. To aid in the proper alignment of the wall sections and the floor sections, we provide a groove 45 in each of the projections 28 and 31 and a groove 40 46 in the bottom of each of the studs 38. In these 45 grooves suitable aligning means, such as a metal shaft 47, may be located.

Having thus seated and aligned the wall sections, the studs 38 may be secured to the projections 27 and 31 by nailing or the like. Since 45 approximately half of the space between the bottom of the building material 40 and the stud 38 is concealed by the floor sections 24, the remaining space is normally concealed by adding a base panel 48.

50 Figures 6, 7, 8 and 9 show in detail the assembly of the upper floor and walls. In this instance, the studs 37 are the supporting means upon which projections 28^a and 31^a are seated and secured. Grooves 45^a and 46^a and aligning means 47^a are preferably used in the assembly of these floors and walls.

It will be apparent from this method of construction and assembly that no space exists 55 between the top of one wall and the bottom of the next through which air might directly circulate between the floors. Also, this construction practically eliminates all possibility of wall and ceiling cracks caused by settling of the walls, for even

when wood joists are used the wall sections, instead of resting upon six or eight inches of shrinkable material, rests upon only a small fraction of this material.

Having described our invention, it will be apparent from the foregoing description that modifications within the scope of this invention will be possible from this disclosure and the applicants preserve the right to make such changes, the detail of construction and application of which may fall within the purview of the appended claims.

What we claim as our invention is:

1. In a building construction, the combination with a supporting means, of a preformed floor 15 section having a portion supported by said means, said section having joists with projections extending from the lower edges of the joists and engageable with the supporting means, filler blocks between the projections forming continuations of the latter transversely of the joist, and a preformed wall section seated on the filler blocks below the top surfaces of the joists.

2. In a building construction, the combination with a supporting means, of a prefabricated floor 25 section having a portion supported by said means, said section having a framework including joists interconnected by cross members and projections extending from the lower portions of the joists engageable with the supporting means, filler 30 blocks secured between the projections and having their upper portions in the same plane as the upper portions of the projections, and a preformed wall section seated on the joists and the blocks below the top surface of the floor section. 35

3. In a building construction, the combination with supporting means, of a preformed floor section having portions supported by said means, including a joist having a projection extending from the lower edge thereof and engageable with the supporting means, a second joist extending parallel to said means and having a portion extending laterally outwardly from the lower longitudinal edge thereof and engageable with said means, and preformed wall sections having their lower edges seated upon the projection and the portion below the top surface of the floor sections.

4. In a building construction, the combination with supporting means, of a preformed floor section having portions supported by said means, 50 including joists provided with projections extending from one end of the joists in a direction of the length of the latter and seated on said means, a second joist extending parallel to said means and having a portion extending laterally 55 outwardly from the lower longitudinal edge thereof and seated on another portion of said supporting means, and preformed wall sections having their lower edges seated upon the projections and the portion below the upper surface 60 of said floor sections.

GAMES SLAYTER.
HOWARD W. COLLINS.
